SPOT LAMP

George E. Gravenstine, Dayton, Ohio, assignor to
The S. H. Thomson Manufacturing Company,
Dayton, Ohio, a corporation of Ohio

Application September 23, 1943, Serial No. 503,476

8 Claims. (Cl. 248—309)

This invention relates to spotlamps and to supports therefor.

It is the principal object of the invention to provide a detachable support, particularly adapted for removably mounting an element such as a spotlamp, which is capable of firmly and reliably supporting such element notwithstanding severe jolting and vibration.

It is also an object to provide a spotlamp having a supporting structure which makes it possible quickly and easily to detach and replace the light on a supporting member, and which holds the light firmly when in place assuring against the loosening and falling thereof even though it is subjected to severe jolting and vibration.

It is also an object to provide a spotlamp adapted to be supported on a vehicle where it is held securely in place during all normal vehicle operation, and from which it can be readily detached without the use of tools and without involving the possible loss of any parts of the supporting structure, for the separate use of the light as a portable device when desired.

Other objects and advantages will be apparent from the following description, the accompanying drawing and the appended claims.

In the drawing:

Fig. 1 is a side elevational view of a spotlamp assembly constructed in accordance with the present invention;

Fig. 2 is a view of the stem member carried by the light itself, this view being on a larger scale than Fig. 1 and shown partially in section;

Fig. 3 is a broken view partially in elevation and partially in section showing the mounting bracket of the light in its assembled relation upon the supporting socket; and

Fig. 4 is a view partially in elevation and partially in section showing the swiveled mounting for the socket.

Referring to the drawing which discloses a preferred embodiment of the invention, a frame 10 is provided which may be generally rectangular in form and which is adapted to be secured in any suitable way to the vehicle or other body with which the lamp is associated. In the case of a lamp for use with a truck, for example, the frame 10 is suitably secured to the truck body in a convenient location such as at the rear thereof where the lamp assembly will be protected against possible damage.

Within the frame 10 is a disk-shaped housing 11 which encloses and rotatably supports a spring reel on which the extension cord 12 is wound. An electrical connection is made through

wires 13 from a suitable power source such as the truck battery, the wires extending into a suitable fitting 14 carried on the hub of the casing. Electrical connection is made from wires 13 through running contacts within the hub to the cord 12 carried on the reel in order that the spotlamp may be continuously energized throughout the winding and unwinding of the reel.

Cord 12 leads to the spotlamp which is shown at 16, being illustrated as comprising a handle grip portion 17 into the end of which the cord 12 extends, a trigger control switch 18 being provided in convenient position for operation by the finger of the hand holding grip 17. The lamp 16 embodies the reflector housing 19 and the lens case 20, the remaining parts of the lamp structure being of suitable construction as desired. An upper hook portion 22 is provided for supporting the lamp from above when removed from its support as shown.

The support for the lamp is carried by frame 10, and comprises a bracket 25 permanently secured to the frame and having an upwardly extending shank portion 26 through which there extends freely the bolt 27. Spring 28 normally acts between the top of the shank and the head of the bolt, and is under suitable tension to frictionally restrain the movement of the bolt to any set position while at the same time permitting rotation thereof by the user when it is desired to rotate the lamp about a vertical axis. At its upper end the bolt is formed with a tongue 30 which is received between the ends of the bifurcated portion 32 of a socket member 33. A wing nut 34 extending through the overlapping parts provides for tightening the parts upon each other to retain the same at any adjusted angular position and upon loosening, provides for movement of the socket to any desired angular relation with respect to the support. The structure as provided thus comprises a swiveled support for socket 33 making it universally adjustable.

An aperture 36 is formed through one wall of the socket 33 at an intermediate point therein, and on the opposite wall of the socket a thumb screw 37 is mounted, being threadedly and adjustably received within the annular socket wall. Preferably the inner end of the thumb screw is enlarged so that while it can be screwed outwardly to a position where the inner end is close to the inner wall of the socket, it cannot be fully withdrawn, and hence cannot be lost.

To the lower side of the lamp casing 19 there is secured a bracket 40, the lower end of which

is provided with a stem member 41 extending downwardly therefrom. The stem is formed with an internal recess 42 extending substantially transversely of the axis of the stem, the recess having one portion of relatively large diameter and another portion of smaller diameter, the two portions being coaxially arranged. One side face of the stem is chamfered as shown at 43, forming a flattened surface at a slight angle to the vertical as illustrated in Fig. 2.

Within recess 42 there is positioned a locking pin 45 having a smooth surfaced end portion adapted to be projected through the small end of the recess. The pin also is formed integrally with an enlarged head portion 46 which is received within the larger part of the recess, the adjacent side wall of the stem above the chamfered part being peaned over as shown at 47 in order to retain the head within the lateral extent of the stem. An expansion spring 48 is received within the larger part of the recess and engages under the head 46 to normally urge the pin into the position shown in Fig. 2 where the head is retained against the peaned portion 47 and the locking end 45 is received inwardly of the stem.

Fig. 3 shows the stem portion assembled in the socket, with the pin 45 being aligned with aperture 36. The inwardly projecting end of thumb screw 37 in relation to the flattened face 43 of the stem forms in effect an interlocking connection, permitting assembly only when the parts are in proper alignment. Upon the tightening of thumb screw 37 the end of that screw engages the head 46 of the locking pin, to move the same axially against the force of spring 48, thereby projecting the end 45 beyond the stem and into aperture 36 in the socket. The end 45 of the locking pin is made to fit closely within the aperture in the socket, and because it is smooth surfaced and free of threads, a firm and secure locking engagement is thereby secured. Further, it will be seen that there is a continuing force developed by spring 48 acting against the end of thumb screw 37, this force being such that even under continual jolting and vibration such as encountered when the light is mounted upon a moving truck, a tight connection is maintained, and the thumb screw is effectively held against any tendency to work loose. When supported in this manner, the lamp may be turned in any desired direction and directed at any desired vertical angle by means of the swiveled supporting structure as described.

When, however, it is desired to remove the lamp from its support and to use it as a portable device, it is only necessary to loosen thumb screw 37, whereupon spring 48 effects the retraction of the locking pin from the socket to a clearance position within the confines of the stem, and the lamp may be then directly removed without the necessity of effecting any separation or disassembly of any parts of the mechanism. Also, when so separated, all parts of the lamp assembly are firmly and securely held together in their own relationship, and hence there is no possibility of any loss of the parts of the mechanism taking place. The lamp may be then removed to the extent permitted by the length of cord 12 on the reel, and upon return the cord is rewound on the reel and it is only necessary to replace the stem within socket 33 in proper alignment as clearly shown and determined by the relation of the flattened face 43 and thumb screw 37. Thereafter the tightening of thumb screw 37 will lock the parts securely in assembled relation.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A support of the character described for detachably supporting a spotlamp or the like which comprises a bracket adapted to be secured to the spotlamp, a stem projecting from said bracket having a transversely extending recess therein, a pin received within said recess and having an end portion adapted to be projected through the stem, means for normally retaining said end portion within the stem, a tubular socket member for receiving said stem internally thereof, and an adjustable member carried by said socket and engageable with said pin to project the end beyond the stem and through an aperture in the socket.

2. A spotlamp assembly of the character described comprising a bracket for attachment to the spotlamp, a stem projecting from said bracket and having a recess extending transversely thereof, a headed pin received within said recess, means for confining the head of said pin against movement outwardly beyond the outer surface of said stem, resilient means within said recess for engaging said head to normally retract the opposite end of said pin within said stem, said resilient means being yieldable upon application of pressure to the headed end of said pin to project said opposite end thereof beyond the stem, a tubular socket member having an aperture in its side wall in position to receive the end of said pin, and an adjustable member carried by said socket opposite said opening to engage the headed end of said pin to project the same into said aperture in locking relation with said socket.

3. A spotlamp assembly comprising a supporting bracket having a stem projecting therefrom, said stem having a recess extending transversely thereof, a locking pin within said recess and normally located inwardly of said stem, a tubular socket adapted to receive said stem in interfitting engagement, said socket having an aperture in the wall thereof opposite said pin in the assembled relation of said parts, means carried by said socket for engaging said pin to project the same into said aperture in locking relation with said socket, and means for yieldably restoring said pin to its said normal position.

4. A detachable support for spotlamps and the like comprising a supporting bracket having a stem projecting therefrom, said stem having a recess extending transversely thereof, a smooth surfaced locking pin within said recess and normally located inwardly of said stem, a tubular socket adapted to receive said stem in interfitting engagement, said socket having an aperture in the wall thereof opposite said pin in the assembled relation of said parts, and a manually operable member threadedly mounted in a wall of said socket for engaging said pin to project the same into said aperture in locking relation with said socket.

5. A detachable support for spotlamps and the like comprising a supporting bracket having a stem projecting therefrom, said stem having a recess extending transversely thereof, a headed locking pin within said recess, resilient means acting against the head of said pin for normally withdrawing the end of said pin inwardly of the

surface of said stem, a tubular socket adapted to receive said stem in interfitting engagement, said socket having an aperture therein opposite said pin in the assembled relation of said parts, and means carried by said socket for engaging the headed end of said pin to project the opposite end thereof to said aperture in locking relation with said socket, said resilient means effecting withdrawal of said pin from said aperture upon withdrawal of said engaging means.

6. A detachable support for spotlamps and the like comprising a supporting bracket having a stem projecting therefrom, said stem having a recess extending transversely thereof, a headed locking pin within said recess, resilient means acting against the head of said pin for normally withdrawing the end of said pin inwardly of the surface of said stem, means on said stem for preventing said head from projecting outwardly of the wall of said stem, a tubular socket adapted to receive said stem in interfitting engagement, said socket having an aperture therein opposite said pin in the assembled relation of said parts, and means carried by said socket for engaging the headed end of said pin to project the opposite end thereof to said aperture in locking relation with said socket, said resilient means effecting withdrawal of said pin from said aperture upon withdrawal of said engaging means.

7. A detachable support for spotlamps and the like comprising a supporting bracket having a stem projecting therefrom, said stem having a recess extending transversely thereof, the side wall of said stem adjacent said recess being chamfered to provide a flattened surface extending in a direction inclined to the axis of said stem, a locking pin within said recess, the wall

of said stem adjacent said chamfered portion being peened over to retain said pin within said recess and within the periphery of said stem, a tubular socket adapted to receive said stem in interfitting engagement, said socket having an aperture therein opposite said pin in the assembled relation of said parts, and a thumb screw threadedly mounted in the wall of said socket opposite said aperture and adapted to engage said pin to project the same from said stem into said aperture in locking relation with said socket.

8. A detachable support for spotlamps and the like comprising a supporting bracket having a stem projecting therefrom, said stem having a recess extending transversely thereof, the side wall of said stem adjacent said recess being chamfered to provide a flattened surface extending in a direction inclined to the axis of said stem, a smooth surfaced locking pin within said recess, the wall of said stem adjacent said chamfered portion being peened over to retain said pin within said recess and within the periphery of said stem, a tubular socket adapted to receive said stem in interfitting engagement, said socket having an aperture therein opposite said pin in the assembled relation of said parts, a thumb screw threadedly mounted in the wall of said socket opposite said aperture and adapted to engage said pin to project the same from said stem into said aperture in locking relation with said socket, and yieldable means for normally urging said pin into withdrawn relation within said recess and developing a continuing pressure against said thumb screw to retain the same against loosening during jolting and vibration.
